CLAIM

The ornamental design for a foldable reusable drinking straw, as shown and described.

DESCRIPTION

FIG. 1 is a top, front, right side perspective view of a first embodiment of a foldable reusable drinking straw, showing my new design;

FIG. 2 is a right side elevational view of the straw of FIG. 1, the left side elevational view being a mirror image thereof;

FIG. 3 is a cross sectional view along lines 3-3 of FIG. 4; FIG. 4 is a front end elevational view of the straw of FIG. 1;

FIG. 5 is a rear end elevational view of the straw of FIG. 1; FIG. 6 is a top, front, right side perspective view of the straw of FIG. 1 partially folded with a storage case in broken lines; FIG. 7 is a top, front, right side perspective view of a second embodiment of a foldable reusable drinking straw, showing my new design;

FIG. 8 is a right side elevational view of the straw of FIG. 7, the left side elevational view being a mirror image thereof;

FIG. 9 is a cross sectional view along lines 9-9 of FIG. 10; FIG. 10 is a front end elevational view of the straw of FIG. 7;

FIG. 11 is a rear end elevational view of the straw of FIG. 7; and,

FIG. 12 is a top, front, right side perspective view of the straw of FIG. 7 partially folded with a storage case in broken lines.

The broken lines in FIGS. 6 and 12 depict environmental subject matter that forms no part of the claimed design.
